FINGER NAIL FILE

Filed March 4, 1927

Harry Schwartzman
INVENTOR

BY Victor J. Evans
ATTORNEY

WITNESS:

UNITED STATES PATENT OFFICE.

HARRY SCHWARTZMAN, OF JERSEY CITY, NEW JERSEY.

FINGER-NAIL FILE.

Application filed March 4, 1927. Serial No. 172,796.

This invention relates to improvements in finger nail files.

The primary object of the invention resides in a nail file in which the finger nails of the user may be evenly trimmed without leaving a rough edge thereon and which usually results by the use of the present style of flat files used for manicure purposes.

Another object of the invention is to provide a manicure instrument having a curved file surface of a shape to receive the finger nail of a user, and which automatically shapes the outer edge of the finger nail during filing operation.

15 A further object of the invention resides in an auxiliary file surface provided on the present style of manicure files for use in applying a finishing touch to the nail after being filed down by the usual file surface provided thereon.

A still further object is to provide a manicure file of the above character which is simple in construction, inexpensive of manufacture, and efficient for the purpose intended.

With these and other objects in view, the invention resides in certain novel construction and combination and arrangement of parts, the essential features of which are hereinafter fully described, are particularly pointed out in the appended claim, and are illustrated in the accompanying drawing, in which:—

Figure 1 is a perspective view of my improved manicure file showing the manner of using the same.

Figure 2 is a side elevation thereof.

Figure 3 is an edge elevation.

Figure 4 is an enlarged vertical sectional view on the line 4—4 of Figure 2.

Figure 5 is a perspective view of a modified form.

Figure 6 is a perspective view of a further modification.

Figure 7 is an edge elevation of the form of my invention shown in Figure 6.

Referring more particularly to the drawing and especially to Figures 1 to 4 inclusive, the reference numeral 10 designates a nail file comprising a body 11 of flat material having a handle portion 12 at one end while the side edges of the body taper toward the opposite end to a point 13. The opposed flat sides of the body are provided with milled or file surfaces 14 and by the use of which, a

person may file their finger nails to the desired length.

Welded or otherwise secured to opposite sides of the handle are plates 15 to provide a thickened portion on the handle adjacent the file surface 14. The handle portion or body of the file has one of its side edges provided with a curved or semi-circular shaped notch or recess 16, while the plates 15 are simultaneously curved as at 17. The inner walls of the curved surfaces of the plates are transversely curved as at 18 so that the inner edges thereof align with the walls of the recess 16 and co-act therewith to provide a grooved recess for the accommodation of the finger nail to be filed. The inner walls of the groove are milled to provide a file surface 19.

In practice, the finger nail to be filed is inserted in the groove so that the same rests and engages the file surface 19, after which the file proper is given a back and forth rocking movement. This movement tends to evenly file the end of the finger nail and simultaneously shapes the nail to provide a smooth rounded edge thereon. By transversely grooving the recess, the finger nail may be filed without fear of the same slipping out. If desired, the user may file the finger nail to the desired length by using the file surface 14, after which the finger nail may be inserted into the groove and trimmed up by the use of the file surface 19.

In Figure 5 of the drawing, I have shown the identical construction of file as shown in the preferred form but the same is applied to a watch chain ornament 20 having a ring 21 at one end and a nail cleaning surface 22 on its other end.

In Figures 6 and 7, I have shown a further modified form of nail file 10', having a handle portion 12' and file surface 14' provided on the flat faces of the body thereof. The flat face of the body of the file is bent or bulged outwardly to provide a semi-circular shaped recess 13', the concave side of which is provided with a file surface 19' for accommodating the finger nail to be filed.

While I have described what I deem to be the most desirable embodiment of my invention, it is obvious that many of the details may be varied without in any way departing from the spirit of my invention, and I therefore do not limit myself to the exact details of construction herein set forth nor

to anything less than the whole of my invention limited only by the appended claim.

What is claimed as new is:—

A finger nail file comprising a flat body
5 having a semi-circular shaped recess provided in one of the side edges thereof and opening onto both flat sides of said body to receive the end of the finger nail of either hand to be filed, a transversely curved longitudinal groove provided in the walls of said

recess and extending the length of the same, and a milled surface provided on the walls of said recess whereby a back and forth rocking movement of said body will produce an even and smooth finish to the end of the finger nail to be filed. 15

In testimony whereof I have affixed my signature.

HARRY SCHWARTZMAN.
